UNITED STATES PATENT OFFICE.

BRUCE BORLAND, OF CHICAGO, ILLINOIS.

FASTENER FOR CONTAINER CAPS.

1,408,857.

Specification of Letters Patent.

Patented Mar. 7, 1922.

Application filed May 16, 1919. Serial No. 297,644.

To all whom it may concern:

Be it known that I, BRUCE BORLAND, a citizen of the United States, residing at Chicago, in the county of Cook and State of Illinois, have invented certain new and useful Improvements in Fasteners for Container Caps, of which the following is a specification.

This invention relates to means for fastening caps or covers formed of paper or the like, on bottles or other containers. These caps are used more or less commonly on milk bottles and it is desirable to have fastening devices which can be cheaply made and readily applied and which can also be easily broken or removed.

The objects of this invention are to provide a simple and efficient fastening device of the character indicated, which may be made of paper or other suitable fabric and readily applied for fastening caps in position; to provide a fastener which may be broken at one side and will hold the cap in condition for further use; and in general to provide a fastener having such novel features as will be disclosed more fully hereinafter.

In the accompanying drawings illustrating this invention:

Fig. 1 is a side view;

Fig. 2 is a plan view of the fastening device; and,

Fig. 3 is a cross-sectional view taken on the line 3—3 of Fig. 1.

The bottle or container 4 represents any ordinary article of this nature, such as a milk bottle or the like. This bottle is provided with a cap or cover 5 having the usual crimp for folded skirt portions 6. These caps are usually formed of disks of paper and the skirt portion must be drawn in and fastened to hold the cap in position over the end of the bottle. As the caps and fasteners are ordinarily used but once, as in connection with milk bottles, such fastening devices must be so constructed that they may be readily applied in an economical manner. In order that these fasteners may meet the commercial requirements, it is also desirable that they should not be injured by moisture and it is also desirable that they can be readily broken without liability of injury to the person opening the bottles.

In accordance with this invention, I pro-

vide a paper band 7 which is held in position by staples which pass through the band and skirt portion of the fastener and are clinched against the surface of the bottle. In order that this band may be readily applied by suitable machinery, it is made in two substantially semi-circular portions 8 and 9, the ends of which overlap a sufficient distance so that they will be engaged by the staples 10 and 11. These two strips of paper or other suitable material are pressed in from the opposite sides of the container and held in position while the staples or fastening devices 10 and 11 are forced into position as shown in Fig. 3. These strips are preferably made of waterproof paper so that they will not be affected by moisture.

When the cap is to be removed, either one or both of the sections 8 and 9 may be broken. If one section only, is broken, the remaining sections with the two staples will hold the corresponding side of the cap in folded position so that it may be again replaced and will serve as a protection or cover until the contents are used. It will be noted that this device will not rust or will not have any jagged projections as occurs when metallic fasteners are used.

Having thus described my invention, what I claim and desire to secure by Letters Patent is:

1. A fastener for a container cap, comprising two substantially semi-circular strips of fabric with overlapping ends and two staples passing through the opposite overlapping ends and engaging with the cap.

2. The combination of a container, a cap fitting over the top of the container, a plurality of strips of paper surrounding the lower portion of the cap and having overlapping ends and staples passing through the overlapping ends and the cap and clinched against the sides of the bottle.

3. The combination with a container having a paper cap, of a fastening band formed of paper or the like and one or more fasteners for attaching the band to the cap for sealing the cap in position.

4. A fastener for a bottle cap, comprising two oppositely disposed strips of paper having overlapping ends and fasteners engaging with said ends and the cap for sealing the parts together.

5. The combination with a bottle, of a cap fitting over the top of the bottle and having a downwardly extending skirt portion, a strip of water-proof paper extending approximately halfway around the skirt portion, and a second strip extending around the opposite side of the skirt portion, said

strips being pressed inwardly to hold the skirt portion against the sides of the bottle, and staples engaging with the ends of the 10 strips and skirt portion and clinched against the bottle for holding the parts together.

BRUCE BORLAND.
